MACHINE FOR FASTENING UPPERS TO
INSOLES

René E. Duplessis, Beverly, Mass., assignor to
United Shoe Machinery Corporation, Flemington, N. J., a corporation of New Jersey

Application June 6, 1941, Serial No. 396,901

48 Claims. (Cl. 12—1)

This invention relates to machines for fastening uppers to insoles. In the manufacture of some kinds of shoes it is the practice to mold the heel part of the upper, unattached to the forepart, before assembling it with an insole and mounting it on the usual last, the heel part being thus molded substantially in final shape and being provided in the molding operation with an inturned flange adapted to overlie the heel end of the insole when the molded heel part is assembled with the insole. An object of the present invention, among others, is to provide means for speedily fastening such molded heel parts to insoles in proper relation to the insoles. In accordance with the present disclosure this object is conveniently accomplished by certain modifications in the structure of a machine of a well-known type commonly used for lasting the heel ends of shoes, but it will be understood that the invention is not thus limited in its applicability and that the novel features are susceptible of various embodiments.

Commercial lasting machines of the above-mentioned type are constructed largely as disclosed in United States Letters Patent No. 1,583,044, granted on May 4, 1926 on an application of C. H. Hoyt, although modified in some respects as further disclosed in other United States Letters Patent, including Letters Patent No. 1,558,737, granted on October 27, 1925 on an application of R. F. McFeely and Letters Patent No. 1,852,015, granted on April 5, 1932 on an application of J. C. Jorgensen. For purposes of this invention the wipers with which such a machine is provided for wiping the margin of the heel end of the upper inwardly over an insole are, as herein illustrated, maintained throughout the operation of the machine in fixed relation to each other while occupying positions commonly known as their advanced and closed positions. They accordingly serve simply as pressing members for pressing the inturned flange of the molded heel part of the upper on the insole in position to be fastened thereto. In the machine herein shown the fastening of the flange to the insole is effected by tack-driving mechanisms supported on these pressing members and constructed as disclosed in the above-mentioned Letters Patent No. 1,852,015. These mechanisms drive a row of tacks through the inturned flange and the insole while the flange is pressed on the insole. While the pressing members are thus maintained in fixed relation to each other during the operation of the machine, they are nevertheless adjustable, together with the tack-driving mechanisms asso-

ciated therewith, for operating on shoe parts of different sizes.

A machine of the above-mentioned type is provided with a work support which is movable in 5 directions lengthwise and heightwise of a shoe thereon to carry the shoe into position to be operated upon, such work-presenting movements of the work support being commonly effected by the operator prior to the starting of the power operation of the machine, substantially as disclosed in the above-mentioned Letters Patent No. 1,558,737. With the pressing members positioned as above described, the work support thus serves to carry the inturned flange of the molded heel 10 part of the upper to a position opposite the pressing members and into engagement with those members, the usual holdown for engaging the insole being omitted. As herein illustrated, the work support has mounted thereon a metal heel-end form on which the insole and the heel part of the upper are positioned, although with obvious modifications of the work support an ordinary last may be used, if desired, in place of such a heel-end form. To assist in positioning the 15 heel part of the upper in proper relation to the form and the insole before its inturned flange is fastened to the insole, it is embraced and clamped against the end and side faces of the form by a heel band such as used heretofore in 20 machines of the illustrated type. The work-presenting movement of the work support in a direction lengthwise of the form serves to carry the rear face of the molded heel part into engagement with the heel band, and the machine 25 herein shown is so constructed that the heel part is thus engaged with the band before the work support receives its movement heightwise of the form toward the flange-pressing means. This affords better insurance that the inturned 30 flange of the heel part, if spaced from the insole, will be properly presented to the pressing means. As the form is then moved heightwise toward the 35 pressing means, the heel band may have a frictional action on the rear face of the heel part tending to seat its inturned flange on the insole before it is pressed on the insole. After the starting of the power operation of the machine 40 the form is moved more forcibly lengthwise toward the band and heightwise toward the pressing means, and the band also is closed about the 45 form, to cause the heel part to be properly positioned and its flange to be pressed firmly on the insole before the fastening tacks are driven.

While a machine embodying features of the present invention may be used to complete the

fastening of a molded heel part to an insole after the forward ends of its inturned flange have already been fastened to the insole in an earlier assembling operation, the machine herein shown is further provided with means whereby it is adapted especially to operate on heel parts which have not been previously assembled with insoles. For this purpose the movable work support has mounted thereon clamping mechanism for engaging and holding the forward ends of the heel part during the movement of the support. As illustrated, this mechanism comprises pads which in response to the movement of a single operating member are moved inwardly to clamp the forward ends of the heel part against the sides of the form and are then moved heightwise of the form with a wiping action on the heel part tending to seat the forward ends of its flange on the insole if they are not already in contact with the insole, and further comprises members which then engage the forward ends of the flange and press them on the insole. The above-mentioned operating member in the machine herein shown is the usual treadle by which in a machine of the illustrated type the operator imparts the work-presenting movements to the work support, the invention providing means whereby the clamping mechanism is operated by this treadle before the work support is moved by the treadle. This clamping mechanism serves to hold the molded heel part and the insole on the form in proper assembled relation during the work-presenting movements of the work support and also assists thereafter in holding the heel part in proper position to be fastened to the insole.

The above and other features of the invention, including various novel details of construction and combinations of parts, will now be more particularly described with reference to the accompanying drawings and thereafter pointed out in the claims.

In the drawings,

Fig. 1 is a view, partly in right-hand side elevation and partly in vertical section, of a portion of a machine of the above-mentioned type as modified for purposes of the present invention, the parts being shown in their initial positions with a molded heel part and an insole mounted on the heel-end form;

Fig. 2 is a view similar to Fig. 1 of a portion of the machine, but showing the parts in the positions which they occupy immediately prior to the tack-driving operation;

Fig. 3 is mainly a plan view on an enlarged scale of the flange-pressing means and the adjusting mechanism associated therewith;

Fig. 4 is a section on the line IV-IV of Fig. 1;

Fig. 5 is a view partly in front elevation and partly in section, showing the work support and the clamping mechanism thereon, this mechanism being shown in its initial position;

Fig. 6 is a view similar to the upper portion of Fig. 5, but showing the clamping mechanism in the position which it occupies after the side-clamping pads have been moved into engagement with the molded heel part but prior to bodily downward movements of their supporting arms;

Fig. 7 is a view similar to Fig. 6, showing the parts as positioned after the downward movements of the arms; and

Fig. 8 is a perspective view of the molded heel part and the insole after the operation of the machine thereon.

The machine is provided with a work support 2 which comprises a post 4 mounted for upward

and downward movements in a casting 6, this casting being mounted for rearward and forward swinging movements about a shaft 8 at its lower end, substantially as disclosed in Letters Patent No. 1,558,737. The post 4, instead of being provided as heretofore with means for supporting an ordinary last, is so constructed as to support at its upper end a metal heel-end form 10 adapted to receive thereon an insole a and the previously molded heel part b of an upper, this heel part being provided with an inturned flange c arranged to overlie the heel end of the insole. For this purpose there is mounted in a slot in the upper end portion of the post a bar 12 having a rectangular upper end arranged to enter a corresponding recess in the form 10 and provided with a shelf 14 on which the form rests. The bar is supported on a bolt 16 for swinging movements about an axis extending widthwise of the form 10 for the purpose of adjusting the bottom or insole-engaging face of the form in proper relation to the flange-pressing means hereinafter described. The bar is adjusted about the bolt 16 by means of a screw 18 threaded in the post 4, this screw being provided with an annular groove into which extend a pair of lugs 20 on the lower end of the bar, one of these lugs being visible in Fig. 1. The post 4 in the construction herein shown is supported initially at the proper height by a collar 22 which is fastened thereto and engages the upper end of the casting 6. At its lower end the post is hollow to receive a diametrically reduced portion 24 of a thimble 26 which has in its larger portion a plurality of pairs of diametrically opposite recesses 28 of different depths to receive selectively a pair of diametrically opposite fingers 30 on the post, substantially as disclosed in Letters Patent No. 1,583,044. Only one of the fingers and three of the recesses are visible in the present drawings. In the construction herein shown a screw 32 extends upwardly into the thimble 26 and is threaded in the diametrically reduced portion 24 of the thimble. As illustrated in Fig. 1, this screw is initially spaced from means, hereinafter described, whereby it is engaged underneath to impart upward movement at the proper time to the post 4, and the parts are so constructed that there is sufficient friction between the post and the thimble 26 to prevent the thimble from moving downwardly relatively to the post. As disclosed in the last-mentioned Letters Patent, such a thimble has been used heretofore to vary the height of the work-supporting post in operating on shoes of different sizes. Since the height of the present post 4 is determined adjustably by the collar 22, the thimble 26 and its screw 32 are used to provide, for any such adjustment of the post, the proper spacing between the head of the screw and the above-mentioned means below it for raising the post. It will be understood that the turning of the screw 32 provides for a finer adjustment than can be obtained by moving the thimble to different positions.

As illustrated in Fig. 1, the work support 2 occupies initially a forwardly inclined position such as to permit the work to be readily mounted on the form 10. Pivotedly connected to the casting 6 is a rearwardly extending rack bar 34 on the rear end of which is a block 36 arranged to engage the frame 38 of the machine to determine the initial position of the work support. This rack bar is movable, as in prior machines, in a guideway in a casting 40 mounted to rock about a shaft 42. From its initial position the work support is swung rearwardly by the operator, through

the use of means hereinafter described, to present the work to the means which operates thereon. By such movement of the work support the rear face of the molded heel part *b* of the upper is carried into engagement with a heel band *44* constructed substantially as heretofore in machines of the illustrated type except that it is somewhat shorter lengthwise of the form. Thereafter the post *4* is raised, as also more particularly hereinafter described, to carry the form upwardly toward pressing means which presses the inturned flange *c* of the heel part down on the insole. This pressing means comprises a pair of pressing members *46*, one of which is shown in Figs. 1 and 2 and the other in Fig. 3, these members being identical in construction with wipers used heretofore for wiping the margin of the heel end of an upper inwardly over an insole, as disclosed in Letters Patent No. 1,852,015. Like those wipers, the members *46* are guided for swinging movements about a common vertical axis, but in the machine herein shown such movements are only for purposes of adjustment in accordance with the size of the shoe being made, the members being maintained throughout the operation of the machine in fixed positions corresponding to the advanced and closed positions of the prior lasting wipers. The guiding means for the members *46*, which is identical with the prior wiper-guiding means, is mounted on a member *48* which corresponds to the slide *28* shown in the last-mentioned Letters Patent, but unlike that slide is held permanently in a fixed position. For this purpose the member *48* is provided with a recess *50* into which extends a tongue *52* formed on a bracket *54* bolted to the frame of the machine. The members *46* are adjusted toward or from each other about their common axis by mechanism constructed substantially as disclosed in the last-mentioned Letters Patent. This mechanism comprises a slide *56* (Figs. 1 and 3) movably mounted in a recess in the member *48* and connected through levers *58* and pinions *60* to slides *62* which are movable in directions widthwise of the form and are connected to the front ends of the members *46*. The slide *56* is connected by lugs *64* to a block *66* in which is threaded a shaft *68* held against lengthwise movement relatively to the member *48* and connected by bevel gears *70* to a short shaft *72* rotatable in the frame. In the construction herein shown the shaft *72* is permanently connected by pinions *74* to a shaft *76* on which is a hand wheel *78*. It will thus be seen that by turning this hand wheel the pressing members *46* may be adjusted relatively to each other as required for operating on shoe parts of different sizes.

Mounted on the pressing members *46* and adjustable with them are tack-driving mechanisms *80*, also constructed as disclosed in Letters Patent No. 1,852,015, which drive tacks through openings in the members and in the machine herein shown thus fasten the inturned flange of the molded heel part of the upper to the insole. Each of these tack-driving mechanisms comprises a block *82* fast on the corresponding member *46* and a group of tack drivers *84* one of which is visible in Fig. 1, the group of drivers being moved downwardly at the proper time by a driver block *86* as fully disclosed in the last-mentioned Letters Patent. A row of tacks *t* (Fig. 8) is thus driven around the end and along the sides of the heel portion of the insole to fasten the molded heel part to the insole, the tacks being clinched on the form *10*.

The previously mentioned rearward swinging movement of the work support and the upward movement of its post *4* prior to the starting of the power operation of the machine are effected by the operator, in a manner generally similar to the movements of the work support in prior machines of the illustrated type, by depression of a treadle *88*. The treadle is connected by a link *90* to the rear end of a lever *92* pivotally mounted between its ends on the casting *6* below the shaft *8*, and the front end of this lever underlies the lower end of a rack bar *94* movable upwardly and downwardly in the casting *6*. Extending upwardly from this rack bar is a rod *96*, and mounted for tipping movements on the upper end of this rod is a nipple *98* arranged to engage the head of the previously mentioned screw *32* to raise the post *4* in response to depression of the treadle *88*. As hereinbefore suggested, and for a purpose hereinafter described, the nipple *98* in the construction herein shown is spaced initially from the screw *32* as illustrated in Fig. 1, the rod *96* being provided with a collar *100* which engages a shoulder on the casting *6* to limit the downward movement of the rod. After the member *98* has been moved upwardly toward the screw *32*, further depression of the treadle *88* serves first, for reasons hereinafter explained, to swing the work support rearwardly about the axis of the shaft *8* until the rear face of the molded heel part of the upper is carried into engagement with the heel band *44*, such swinging movement of the work support by the treadle being due to the leverage afforded by the rear arm of the lever *92* and that portion of the casting *6* which is below the shaft *8*. By reason of the resistance to further swinging movement of the work support upon engagement of the molded heel part with the heel band, still further depression of the treadle thereafter serves to swing the lever *92* about its connection with the casting *6* and thereby, through the rack bar *94* and the rod *96*, to raise the post *4*. In this manner the form *10* is moved upwardly toward the pressing members *46* to cause them to press the inturned flange *c* down on the insole. If the heel part is not so positioned on the form that its flange *c* is actually carried into engagement with the members *46* by the rearward swinging movement of the work support, such upward movement of the form carries the flange into engagement with these members, the heel band *44* having a frictional action on the rear face of the heel part which tends to seat the flange on the insole before it is pressed thereon by the members *46*. To render the heel band thus effective, it is so controlled that, as distinguished from prior machines of the illustrated type, it can have no upward movement. For this purpose the usual angular clip *102* which is fastened to the rear end of the band and connects it to its supporting slide *104* is seated against a washer *106* in engagement with the lower face of the slide. To prevent the heel band from rubbing too hard on the rear face of the molded heel part, the previously mentioned casting *40* is provided with a bumper *108* which is engaged by a lug *110* on the rack bar *94* and is thereby moved rearwardly against the resistance of a spring *112* just before the heel part engages the heel band. This mechanism is similar to that used heretofore for initiating forward movement of the work support in the return of the parts to their starting positions and has that function also in the machine herein shown.

75 The machine herein shown is further provided

with means for clamping and holding the molded heel part and the insole in proper relation to each other and to the form during the movements of the work support, this means assisting also thereafter in holding the heel part in proper position to be fastened to the insole. For the purpose in view there is clamped on the post 4 by a screw 114 a bracket 116, and supported on this bracket for downward and upward movements is a yoke-shaped holder 118. Fast in this holder is a downwardly extending sleeve 120 which is movable in a bearing in the bracket, and the holder engages flat faces 122 (Fig. 4) on the bracket to prevent it from turning about the axis of the sleeve. A spring 124 mounted in a socket in the bracket 116 and engaging a lug 126 on the holder 118 tends to raise the holder and maintains it initially in a position determined by engagement of a flange 128 (Figs. 1 and 5) on the lower end of the sleeve 120 with the bracket. Mounted to swing about rods 130 on the holder 118 are levers 132 having upwardly extending arms 134 which carry pads 136 arranged to engage the forward end portions of the molded heel part of the upper and to press them inwardly against the sides of the form. The pads may be made of rubber or other material suitable for engagement with the heel part without injury to its surface. The levers 132 have also downwardly extending arms 138 connected by a pair of toggle links 140 to the head 142 of a rod 144 which is movable in the previously mentioned sleeve 120. At its lower end this rod is connected by a coupling 146 to the upper end of a rod 148 which extends downwardly into a sleeve 150 and is provided at its lower end with a nut 152. Between this nut and a thimble 154 which is threaded in the upper end of the sleeve 150 and through which the rod 148 may slide is a spring 156. The lower end of the sleeve 150 is connected by a coupling 158 to the front end of a lever 160 pivotally mounted between its ends on a bracket 162 fast on the casting 6. The rear end of the lever 160 is connected by a link 164 to the front end of the previously mentioned treadle-operated lever 92. It will thus be seen that in response to depression of the treadle 88 upward movement is imparted to the link 164 and downward movement to the sleeve 150, and that this sleeve acts through the spring 156 to impart downward movements to the rods 148 and 144, the rod 144 acting through the toggle links 140 to impart inward swinging movements to the lever arms 134 and thereby to cause the pads 136 to press the forward ends of the heel part against the sides of the form. By reason of the resistance of the form to further swinging movements of the arms 134, further depression of the treadle then causes the holder 118 to move downward against the resistance of the spring 124 and thus to carry the arms bodily downward, causing the pads 136 to have a downward wiping action on the forward ends of the heel part. This serves to seat the forward ends of the inturned flange of the heel part on the insole if they are not already in contact with the insole. By such bodily downward movements of the arms 134 inwardly extending fingers 166 formed on the upper ends of the arms are also caused to engage the forward ends of the inturned flange and to press them down on the insole. It is to permit these operations to be performed by depression of the treadle 88 prior to the rearward swinging movement of the work support that provision is afforded, as hereinbefore described, for lost motion between the member 98 and the screw 32. To insure that no

10 swinging movement of the work support will occur until the forward ends of the heel part have thus been clamped, there is provided a spring 168 (Fig. 1) which is connected to a pin 170 on the rear end of the rack bar 34 and to a plate 172 in engagement with the front of the frame 38 and tends to resist the swinging of the work support. It will be understood that the swinging of the support takes place in response to further depression of the treadle by reason of the resistance of the work to downward movements of the arms 134. After the swinging of the support the spring 156 in the sleeve 150 is yieldable to permit such further depression of the treadle as is required to raise the post 4. It will be noted that since the bracket 116 is fast on the post 4, the clamping mechanism supported on the bracket moves upwardly with the post, the spring 156 also yielding to permit this.

20 After the operator has swung the work support rearwardly and raised the post 4 by the treadle 88 as above described, he starts the power operation of the machine. Thereafter the heel band 44 is closed by power to press the molded heel part in close conformity to the sides of the form by the operation of mechanism disclosed in detail in Letters Patent No. 1,583,044. A portion of this mechanism is shown in Fig. 1 and comprises a pinion 174 which imparts rearward movement to a slide 176, this slide acting through a spring 178 to operate members (not herein shown) whereby the heel band is pressed inwardly toward the sides of the form. Also as in prior machines of the illustrated type, the movement of the slide 176 serves to operate mechanism for imparting further rearward movement to the work support and further upward movement to its post 4, thus causing the heel band to press more firmly on the rear face of the molded heel part and causing its inturned flange to be pressed more firmly down on the insole. This mechanism comprises a bell-crank lever 180 operated by the slide 176 and connected by a link 182 to a pawl carrier 184 on the shaft 42, the pawl carrier being provided with a pawl 186 which is arranged to engage a ratchet wheel 188 and thereby to turn a pinion 190 engaging the rack bar 34. The bell-crank lever 180 is also connected by a link 192 to a pawl carrier 194 which is mounted on the shaft 8 and is provided with pawls 196 arranged to engage a ratchet wheel 198 on the shaft and thereby to turn a pinion 200 in engagement with the previously mentioned rack bar 34. The link 192 is a two-part link the upper part of which is provided at its lower end with an abutment 202 which acts yieldingly through a spring 204 on a cylindrical casing 206 connected to the lower part of the link. In machines of the illustrated type as heretofore constructed the slide 176 receives two successive movements in the direction to operate the heel band and the work support in time relation to repeated overwiping movements of the lasting wipers, and the slide may be operated in this manner consistently with the objects of the present invention if it is desired to adapt an existing machine for the purpose in view with as few changes as possible, although but one such movement of the slide is necessary for the proper treatment of the work. Prior machines of the illustrated type have further been provided with additional means, including the lever 172 shown in Letters Patent No. 1,583,044, for imparting yieldingly to the work support movement in the direction to press the work against the heel band

prior to the closing of the band, and preferably although not necessarily such means will be included in a machine constructed for the purposes herein disclosed.

To afford better insurance that the molded heel part will conform closely to the edge of the insole all around the heel end of the insole before the fastenings are driven, the work is preferably assembled by the operator on the form in the manner illustrated in Fig. 1 with the rear portion of the heel part tipped upward somewhat relatively to the form and the insole and with the insole pressed back against the heel part as thus positioned, after which the forward ends of the heel part are clamped against the form and the insole in the manner hereinbefore described. Thereafter the upward movement of the form 10 toward the pressing members 46 tends to crowd portions of the rear end of the heel part which are immediately below its inturned flange in a rearward direction while maintaining them in contact with the edge of the insole until the flange is finally pressed on the insole. This has a tensioning effect lengthwise of the form on the opposite side portions of the heel part adjacent to the flange; and if the force acting in this manner is great enough, depending upon how much the rear portion of the flange is initially spaced above the insole, the forward ends of the heel part may slip somewhat in a rearward direction relatively to the clamping members in contact therewith. In these respects the machine herein shown is adapted to carry out a novel method claimed in my copending application Serial No. 396,902 filed on June 6, 1941.

The manner of operation of the machine will now be briefly summarized. The operator first mounts a molded heel part and an insole on the form 10 in the manner illustrated in Fig. 1, and then by depression of the treadle 88 operates the clamp arms 134 to clamp the forward ends of the heel part against the form and the insole. In this operation the pads 136 are first moved into clamping engagement with the sides of the heel part (Fig. 6) and the arms 134 are then moved bodily downward a short distance to cause the pads to wipe the end portions of the heel part in a downward direction and then to cause the fingers 166 to clamp the ends of the inturned flange down on the insole (Fig. 7). Further depression of the treadle 88 then serves to swing the work support rearwardly to carry the rear face of the molded heel part into engagement with the heel band 44 and thereafter to raise the post 4 to move the form upwardly toward the pressing members 46. In this upward movement, if the parts of the work are initially presented as shown in Fig. 1, the form serves to force the extreme rear end of the insole toward the inturned flange c while maintaining close contact of the edge of the insole with the rear portion of the heel part, as hereinbefore explained, and then to press the insole against the flange and the flange against the members 46 rearwardly of the clamping fingers 166 which are still in clamping engagement with the forward ends of the flange. In this operation also, under some conditions, the heel band 44 may have a downward wiping action on the rear face of the heel part, as hereinbefore explained. The operator next starts the power operation of the machine, and in the course of its operation the heel band 44 is closed to press the opposite side portions of the heel part rearwardly of the pads 136 against the form, the

work support is operated to move the form with greater force in rearward and upward directions, and then the tack-driving mechanisms are operated to fasten the flange of the heel part to the insole, the points of the tacks being clinched on the form. The operator continues to hold the treadle 88 depressed and thereby to maintain the clamping pressure on the forward ends of the molded heel part at least until near the end of the cycle of operations of the machine. In the return of the parts to starting positions the work support is swung forwardly to present the work in position to be removed from the form, the work then having the appearance illustrated in Fig. 8.

As hereinbefore suggested, the machine may be used, if desired, to operate in the manner described on work positioned on an ordinary last instead of on a metal form such as herein shown, the work support being modified in such manner as to support a last as in prior lasting machines of the same general type. Accordingly, the term "form" as used in the appended claims is intended, unless otherwise required by the context, to include a last as well as a form of the character herein illustrated. It will also be recognized that the machine may be used to fasten the previously molded heel portion of a full-length upper to an insole, and unless required by the context, therefore, the term "heel part" as used in the claims is not intended to be limited to a heel part which is unattached to the forepart.

Having described the invention, what I claim as new and desire to secure by Letters Patent of the United States is:

1. In a machine for fastening uppers to insoles, a support for a form having thereon an insole and the heel part of an upper previously molded to provide an inturned flange to overlie the heel end of the insole, pressing means for engaging said inturned flange around the heel end of the insole and for pressing it on the insole, said pressing means comprising members arranged respectively to engage the flange along the opposite sides of the heel end of the insole and fixed relatively to each other during the operation of the machine, said members being relatively adjustable by the operator prior to the operation of the machine in accordance with the size of the shoe being made, and mechanism for effecting relative movement of said support and pressing means in a direction heightwise of the form to press said flange on the insole in position to be fastened thereto.

2. In a machine for fastening uppers to insoles, a support for a form having thereon an insole and the heel part of an upper previously molded to provide an inturned flange to overlie the heel end of the insole, pressing means for engaging said inturned flange around the heel end of the insole and for pressing it on the insole, said pressing means comprising members arranged respectively to engage the flange along the opposite sides of the heel end of the insole and fixed relatively to each other during their engagement with the flange, said members being relatively adjustable in accordance with the size of the shoe being made, mechanism for effecting relative movement of said support and pressing means in a direction heightwise of the form to press said flange on the insole, and means for driving a row of fastenings through said flange around the end and along the sides of the

heel portion of the insole to fasten the flange to the insole while it is pressed thereon.

3. In a machine for fastening uppers to insoles, a support for a form having thereon an insole and the heel part of an upper previously molded to provide an inturned flange to overlie the heel end of the insole, pressing means for engaging said inturned flange around the heel end of the insole and for pressing it on the insole, said pressing means comprising members arranged respectively to engage the flange along the opposite sides of the heel end of the insole, means for adjusting said members relatively to each other by swinging them widthwise of the form and for thereafter maintaining them in fixed relation to each other during the operation of the machine, mechanism for effecting relative movement of said support and members in a direction heightwise of the form to press said flange on the insole, and means for driving a row of fastenings through said flange around the end and along the sides of the heel portion of the insole to fasten the flange to the insole while it is pressed thereon.

4. In a machine for fastening uppers to insoles, a support for a form having thereon an insole and the heel part of an upper previously molded to provide an inturned flange to overlie the heel end of the insole, pressing means for engaging said inturned flange around the heel end of the insole and for pressing it on the insole, said pressing means comprising members arranged respectively to engage the flange along the opposite sides of the heel end of the insole and fixed relatively to each other during their engagement with the flange, said members being relatively adjustable in accordance with the size of the shoe being made, means for effecting relative movement of said support and members in a direction heightwise of the form to press said flange on the insole, and mechanisms associated respectively with said different members and relatively adjustable with them for driving fastenings through said flange around the heel end of the insole to fasten the flange to the insole while it is pressed thereon.

5. In a machine for fastening uppers to insoles, a support for a form having thereon an insole and the heel part of an upper previously molded to provide an inturned flange to overlie the heel end of the insole, pressing means for engaging said inturned flange around the heel end of the insole and for pressing it on the insole, said support being movable to carry the flange into engagement with said pressing means at the end and sides of the heel portion of the insole, and means for driving fastenings through said flange to fasten it to the insole while it is pressed thereon.

6. In a machine for fastening uppers to insoles, a support for a form having thereon an insole and the heel part of an upper previously molded to provide an inturned flange to overlie the heel end of the insole, pressing means for engaging said inturned flange around the heel end of the insole and for pressing it on the insole, said pressing means comprising relatively adjustable members arranged respectively to engage the flange along the opposite sides of the heel end of the insole and fixed relatively to each other during their engagement with the flange, said support being movable to carry the flange into engagement with said members, and means for driving fastenings through said flange

to fasten it to the insole while it is pressed thereon.

7. In a machine for fastening uppers to insoles, a support for a form having thereon an insole and the heel part of an upper previously molded to provide an inturned flange to overlie the heel end of the insole, pressing means for engaging said inturned flange around the heel end of the insole and for pressing it on the insole, said pressing means comprising members arranged respectively to engage the flange along the opposite sides of the heel end of the insole and fixed relatively to each other during the operation of the machine, and means for adjusting said members relatively to each other widthwise of the form in accordance with the size of the shoe being made, said support being movable to carry the flange into engagement with said members and to cause them to press it on the insole in position to be fastened thereto.

8. In a machine for fastening uppers to insoles, a support for a form having thereon an insole and the heel part of an upper previously molded to provide an inturned flange to overlie the heel end of the insole, pressing means for engaging said inturned flange around the heel end of the insole and for pressing it on the insole, said support being movable in directions lengthwise and heightwise of the form to carry said flange to a position opposite said pressing means and into engagement with the pressing means at the end and sides of the heel portion of the insole, and means for driving fastenings through the flange to fasten it to the insole while it is pressed thereon.

9. In a machine for fastening uppers to insoles, a support for a form having thereon an insole and the heel part of an upper previously molded to provide an inturned flange to overlie the heel end of the insole, pressing means for engaging said inturned flange around the heel end of the insole and for pressing it on the insole, said pressing means comprising members arranged respectively to engage the flange along the opposite sides of the heel end of the insole and fixed relatively to each other during the operation of the machine, and means for adjusting said members relatively to each other widthwise of the form in accordance with the size of the shoe being made, said support being movable in directions lengthwise and heightwise of the form to carry the flange to a position opposite said members and to cause them to press it on the insole in position to be fastened thereto.

10. In a machine for fastening uppers to insoles, a support for a form having thereon an insole and the heel part of an upper previously molded to provide an inturned flange to overlie the heel end of the insole, pressing means for engaging said inturned flange around the heel end of the insole and for pressing it on the insole, said support being movable by the operator to carry the flange into engagement with said pressing means at the end and sides of the heel portion of the insole, and power-operated means for further moving said support to cause the pressing means to press the flange on the insole in position to be fastened thereto.

11. In a machine for fastening uppers to insoles, a support for a form having thereon an insole and the heel part of an upper previously molded to provide an inturned flange to overlie the heel end of the insole, pressing means for engaging said inturned flange around the heel end of the insole and for pressing it on the in-

sole, means movable by the operator for moving said support in directions lengthwise and heightwise of the form to carry the flange to a position opposite said pressing means and into engagement with said pressing means at the end and sides of the heel portion of the insole, and power-operated means for further moving said support in a direction heightwise of the form to cause said pressing means to press the flange on the insole in position to be fastened thereto.

12. In a machine for fastening uppers to insoles, a support for a form having thereon an insole and the heel part of an upper previously molded to provide an inturned flange to overlie the heel end of the insole, pressing means for engaging said inturned flange around the heel end of the insole and for pressing it on the insole, said support being movable by the operator to carry the flange into engagement with said pressing means at the end and sides of the heel portion of the insole, power-operated means for further moving said support to cause the pressing means to press the flange on the insole, and power-operated means for driving fastenings through the flange to fasten it to the insole while it is pressed thereon.

13. In a machine for fastening uppers to insoles, a support for a form having thereon an insole and the heel part of an upper previously molded to provide an inturned flange to overlie the heel end of the insole, pressing means for engaging said inturned flange around the heel end of the insole and for pressing it on the insole, said support being movable by the operator in directions lengthwise and heightwise of the form to carry the flange to a position opposite said pressing means and into engagement with said pressing means at the end and sides of the heel portion of the insole, power-operated means for further moving said support in a direction heightwise of the form to cause said pressing means to press the flange on the insole, and power-operated means for driving fastenings through the flange to fasten it to the insole while it is pressed thereon.

14. In a machine for fastening uppers to insoles, a support for a form having thereon an insole and the heel part of an upper previously molded to provide an inturned flange to overlie the heel end of the insole, means for clamping said molded heel part against the end and side faces of the form, pressing means for engaging said inturned flange around the heel end of the insole and for pressing it on the insole, said pressing means having relatively adjustable portions arranged respectively to engage the flange along the opposite sides of the heel end of the insole and fixed relatively to each other during the operation of the machine, and mechanism for effecting relative movement of said support and pressing means in a direction heightwise of the form to press said flange on the insole in position to be fastened thereto.

15. In a machine for fastening uppers to insoles, a support for a form having thereon an insole and the heel part of an upper previously molded to provide an inturned flange to overlie the heel end of the insole, means for clamping said molded heel part against the end and side faces of the form, pressing means for engaging said inturned flange around the heel end of the insole and for pressing it on the insole, said pressing means having relatively adjustable portions arranged respectively to engage the flange along the opposite sides of the heel end of the

insole and fixed relatively to each other during their engagement with the flange, and means for driving fastenings through said flange around the heel end of the insole to fasten the flange to the insole while it is pressed thereon.

16. In a machine for fastening uppers to insoles, a support for a form having thereon an insole and the heel part of an upper previously molded to provide an inturned flange to overlie the heel end of the insole, means for clamping said molded heel part against the end and side faces of the form, pressing means for engaging said inturned flange around the heel end of the insole and for pressing it on the insole, said pressing means comprising members arranged respectively to engage the flange along the opposite sides of the heel end of the insole and fixed relatively to each other during the operation of the machine, said members being relatively adjustable in accordance with the size of the shoe being made, and mechanism associated respectively with said different members and relatively adjustable with them for driving fastenings through said flange around the heel end of the insole to fasten the flange to the insole while it is pressed thereon.

17. In a machine for fastening uppers to insoles, a support for a form having thereon an insole and the heel part of an upper previously molded to provide an inturned flange to overlie the heel end of the insole, means for clamping said molded heel part against the end and side faces of the form, and pressing means for engaging said inturned flange around the heel end of the insole and for pressing it on the insole in position to be fastened thereto, said support being movable in directions lengthwise and heightwise of the form to carry said molded heel part into engagement with said clamping means and to carry its inturned flange into engagement with said pressing means at the end and sides of the heel portion of the insole.

18. In a machine for fastening uppers to insoles, a support for a form having thereon an insole and the heel part of an upper previously molded to provide an inturned flange to overlie the heel end of the insole, means for clamping said molded heel part against the end and side faces of the form, pressing means for engaging said inturned flange around the heel end of the insole and for pressing it on the insole, said support being movable in directions lengthwise and heightwise of the form to carry said molded heel part into engagement with said clamping means and to carry its inturned flange into engagement with said pressing means at the end and sides of the heel portion of the insole, and means for driving fastenings through said flange to fasten it to the insole while it is pressed thereon.

19. In a machine for fastening uppers to insoles, a support for a form having thereon an insole and the heel part of an upper previously molded to provide an inturned flange to overlie the heel end of the insole, a heel band for embracing said molded heel part and for clamping it against the form, pressing means for engaging said inturned flange around the heel end of the insole and for pressing it on the insole, said support being movable in directions lengthwise and heightwise of the form to carry the rear face of said molded heel part into engagement with the heel band and to carry its inturned flange into engagement with said pressing means at the end and sides of the heel portion of the insole, power-operated means for thereafter closing the heel

band about the form, and power-operated means for driving fastenings through said flange to fasten it to the insole while it is pressed thereon.

20. In a machine for fastening uppers to insoles, a support for a form having thereon an insole and the heel part of an upper previously molded to provide an inturned flange to overlie the heel end of the insole, a heel band for embracing said molded heel part and for clamping it against the form, pressing means for engaging said inturned flange around the heel end of the insole and for pressing it on the insole, said support being movable by the operator in directions lengthwise and heightwise of the form to carry the rear face of said molded heel part into engagement with the heel band and to carry its inturned flange into engagement with said pressing means at the end and sides of the heel portion of the insole, power-operated means for thereafter closing the heel band about the form and for moving the form heightwise to cause said pressing means to press said flange on the insole, and power-operated means for driving fastenings through said flange to fasten it to the insole while it is pressed thereon.

21. In a machine for fastening uppers to insoles, a support for a form having thereon an insole and the heel part of an upper previously molded to provide an inturned flange to overlie the heel end of the insole, means for clamping said molded heel part against the form, pressing means for engaging said inturned flange around the heel end of the insole and for pressing it on the insole, and mechanism for effecting relative movement of said support and clamping means to cause said clamping means to act frictionally on the heel part in the direction to seat its inturned flange on the insole and for also effecting relative movement of said support and pressing means to cause the pressing means to press the flange on the insole.

22. In a machine for fastening uppers to insoles, a support for a form having thereon an insole and the heel part of an upper previously molded to provide an inturned flange to overlie the heel end of the insole, means for clamping said molded heel part against the end face of the form, pressing means for engaging said inturned flange around the heel end of the insole and for pressing it on the insole, and means for moving said support in a direction heightwise of the form toward the pressing means and relatively to the clamping means to cause said clamping means to act frictionally on the rear face of the molded heel part in the direction to seat its inturned flange on the insole and to cause said pressing means to press the flange on the insole.

23. In a machine for fastening uppers to insoles, a support for a form having thereon an insole and the heel part of an upper previously molded to provide an inturned flange to overlie the heel end of the insole, means for clamping said molded heel part against the end face of the form, and pressing means for engaging said inturned flange around the heel end of the insole and for pressing it on the insole, said support being movable in a direction lengthwise of the form to carry the heel part into engagement with said clamping means and movable thereafter in a direction heightwise of the form toward the pressing means and relatively to the clamping means to cause said clamping means to act frictionally on the heel part in the direction to seat its inturned flange on the insole and to cause

said pressing means to press the flange on the insole.

24. In a machine for fastening uppers to insoles, a support for a form having thereon an insole and the heel part of an upper previously molded to provide an inturned flange to overlie the heel end of the insole, means for clamping said molded heel part against the end face of the form, pressing means for engaging said inturned flange around the heel end of the insole and for pressing it on the insole, said support being movable by the operator in a direction lengthwise of the form to carry the molded heel part into engagement with said clamping means and movable thereafter by the operator in a direction heightwise of the form toward the pressing means and relatively to the clamping means to cause said clamping means to act frictionally on the molded heel part in the direction to seat its flange on the insole and to cause the pressing means to press the flange on the insole, and power-operated means for thereafter further operating said support to increase the pressure of said clamping means and pressing means on the heel part.

25. In a machine for fastening uppers to insoles, a support for a form having thereon an insole and the heel part of an upper previously molded to provide an inturned flange to overlie the heel end of the insole, a heel band for embracing said molded heel part and for clamping it against the form, pressing means for engaging said inturned flange around the heel end of the insole and for pressing it on the insole, said support being movable by the operator in a direction lengthwise of the form to carry the heel part into engagement with said heel band and movable thereafter by the operator in a direction heightwise of the form toward the pressing means and relatively to the heel band to cause the heel band to act frictionally on the heel part in the direction to seat its flange on the insole and to cause said pressing means to press the flange on the insole, and power-operated means for thereafter closing the heel band about the form and for further moving said support to cause the pressing means to press said flange more firmly on the insole.

26. In a machine for fastening uppers to insoles, a support for a form having thereon an insole and the heel part of an upper previously molded to provide an inturned flange to overlie the heel end of the insole, means for positioning said molded heel part on the form with the forward ends of its inturned flange in engagement with the insole and with the rear portion of said flange spaced from the insole heightwise of the form, and mechanism for effecting relative movement of said heel part and the form to seat the rear portion of the flange also on the insole while the heel part is controlled by said positioning means.

27. In a machine for fastening uppers to insoles, a support for a form having thereon an insole and the heel part of an upper previously molded to provide an inturned flange to overlie the heel end of the insole, clamping means for engaging the forward ends of said molded heel part to position it relatively to the form and the insole with the forward ends of its inturned flange in engagement with the insole and with the rear portion of said flange spaced from the insole heightwise of the form, and mechanism for effecting relative movement of said heel part and the form to seat the rear portion of the

flange also on the insole while the forward ends of the heel part are controlled by said clamping means.

28. In a machine for fastening uppers to insoles, a support for a form having thereon an insole and the heel part of an upper previously molded to provide an inturned flange to overlie the heel end of the insole, means for clamping the forward ends of said inturned flange on the insole to position the heel part and the insole relatively to the form with the rear portion of the heel part in engagement with the rear edge of the insole but with the rear portion of the flange spaced from the insole heightwise of the form, and mechanism for effecting relative movement of said heel part and the form to seat the rear portion of the flange also on the insole while its forward ends are controlled by said clamping means.

29. In a machine for fastening uppers to insoles, a support for a form having thereon an insole and the heel part of an upper previously molded to provide an inturned flange to overlie the heel end of the insole, means for clamping the forward ends of said inturned flange on the insole with said molded heel part tipped relatively to the form to space the rear portion of its flange from the insole heightwise of the form, pressing means for engaging said flange rearwardly of said clamping means, and mechanism for effecting relative movement of said pressing means and the form in a direction heightwise of the form to seat the rear portion of the flange also on the insole while its forward ends are controlled by said clamping means.

30. In a machine for fastening uppers to insoles, a support for a form having thereon an insole and the heel part of an upper previously molded to provide an inturned flange to overlie the heel end of the insole, clamping means for engaging the forward ends of said molded heel part to position it relatively to the form and the insole with the forward ends of its inturned flange in engagement with the insole and with the rear portion of said flange spaced from the insole heightwise of the form, pressing means for engaging said flange rearwardly of said clamping means, and means for moving the form heightwise toward said pressing means to bring the rear end of the insole into engagement with said flange while the forward ends of the heel part are controlled by said clamping means.

31. In a machine for fastening uppers to insoles, a support for a form having thereon an insole and the heel part of an upper previously molded to provide an inturned flange to overlie the heel end of the insole, pressing means for engaging said inturned flange around the heel end of the insole and for pressing it on the insole, said pressing means having portions arranged respectively to engage the flange along the opposite sides of the heel end of the insole and fixed relatively to each other during their engagement with the flange, said support being movable in a direction lengthwise of the form to carry said heel part to a position in which its inturned flange is located opposite said pressing means, and means movable with said support for clamping and holding the forward ends of the molded heel part during the movement of the support.

32. In a machine for fastening uppers to insoles, a support for a form having thereon an insole and the heel part of an upper previously molded to provide an inturned flange to overlie the heel end of the insole, pressing means for en-

gaging said inturned flange around the heel end of the insole and for pressing it on the insole, said pressing means having portions arranged respectively to engage the flange along the opposite sides of the heel end of the insole and fixed relatively to each other during their engagement with the flange, said support being movable in a direction lengthwise of the form to carry said heel part to a position in which its inturned flange is located opposite said pressing means, and mechanism carried by said support for clamping the forward ends of the molded heel part against the sides of the form and for clamping the forward ends of its inturned flange against the insole to hold the heel part and the insole in proper relation to each other and to the form during the movement of the support.

33. In a machine for fastening uppers to insoles, a support for a form having thereon an insole and the heel part of an upper previously molded to provide an inturned flange to overlie the heel end of the insole, means for fastening said flange to the insole, said support being movable in a direction lengthwise of the form to present said molded heel part and the insole to the fastening means, and mechanism movable with said support for engaging the forward ends of said heel part to control it during the movement of the support, said mechanism comprising members movable laterally of the form to clamp the forward ends of the heel part against the sides of the form and movable thereafter heightwise of the form with a wiping action on said heel part tending to seat the forward ends of its inturned flange on the insole, said members being provided with means for clamping the forward ends of the inturned flange on the insole in response to their movements heightwise of the form.

34. In a machine for fastening uppers to insoles, a support for a form having thereon an insole and the heel part of an upper previously molded to provide an inturned flange to overlie the heel end of the insole, means for fastening said flange to the insole, said support being movable in a direction lengthwise of the form to present said molded heel part and the insole to the fastening means, mechanism movable with said support for engaging the forward ends of said heel part to control it during the movement of the support, said mechanism comprising arms mounted for swinging movements laterally of the form and having means thereon for clamping the forward ends of the heel part against the sides of the form, and means for swinging said arms into clamping positions and for thereafter moving them bodily heightwise of the form with a wiping action on said heel part tending to seat the forward ends of its inturned flange on the insole, said arms having means for clamping the forward ends of said flange on the insole in response to their bodily movements.

35. In a machine for fastening uppers to insoles, a support for a form having thereon an insole and the heel part of an upper previously molded to provide an inturned flange to overlie the heel end of the insole, means for fastening said flange to the insole, said support being movable in a direction lengthwise of the form to present said molded heel part and the insole to the fastening means, mechanism movable with said support for engaging the forward ends of said heel part to control it during the movement of the support, said mechanism comprising arms mounted for swinging movements laterally of the form to clamp the forward ends of the heel part

against the sides of the form, a toggle for thus swinging said arms, means for operating said toggle, and a support for said arms yieldingly movable with them heightwise of the form in response to further movement of said operating means after the clamping of the heel part against the sides of the form, said arms having means for clamping the forward ends of the inturned flange on the insole in response to such movement of the arms heightwise of the form.

36. In a machine for fastening uppers to insoles, a support for a form having thereon an insole and the heel part of an upper previously molded to provide an inturned flange to overlie the heel end of the insole, means for fastening said flange to the insole, said support being movable in a direction lengthwise of the form to present said molded heel part and the insole to the fastening means, clamping mechanism movable with said support for engaging the forward ends of said heel part to control it during the movement of the support, a treadle for thus moving the support, and means for operating said clamping mechanism also by said treadle prior to the movement of the support.

37. In a machine for fastening uppers to insoles, a support for a form having thereon an insole and the heel part of an upper previously molded to provide an inturned flange to overlie the heel end of the insole, means for fastening said flange to the insole, said support being movable in a direction lengthwise of the form to present said molded heel part and the insole to the fastening means, clamping mechanism movable with said support for engaging the forward ends of said heel part to control it during the movement of the support, a treadle movable to operate said clamping mechanism and further movable thereafter to impart the work-presenting movement to said support, and means for yieldingly resisting the movement of the support to prevent its movement by the treadle until after the operation of the clamping mechanism by the treadle.

38. In a machine for fastening uppers to insoles, a support for a form having thereon an insole and the heel part of an upper previously molded to provide an inturned flange to overlie the heel end of the insole, means for fastening said flange to the insole, said support being movable in a direction lengthwise of the form to present said molded heel part and the insole to the fastening means, clamping mechanism carried by said support for engaging the forward ends of said heel part to control it during the movement of the support, a treadle movable to operate said clamping mechanism and further movable thereafter to impart the work-presenting movement to said support, and mechanism for moving the form thereafter heightwise toward said fastening means by still further movement of said treadle.

39. In a machine for fastening uppers to insoles, a support for a form having thereon an insole and the heel part of an upper previously molded to provide an inturned flange to overlie the heel end of the insole, means for fastening said flange to the insole, said support being movable in a direction lengthwise of the form to present said molded heel part and the insole to the fastening means, clamping mechanism carried by said support for engaging the forward ends of said heel part to control it during the movement of the support, a treadle movable to operate said clamping mechanism and further movable thereafter to impart the work-present-

ing movement to said support, and mechanism for moving the form thereafter heightwise toward said fastening means by still further movement of said treadle, said last-named mechanism comprising members relatively movable idly by the treadle to prevent heightwise movement of the form during the operation of said clamping mechanism.

40. In a machine for fastening uppers to insoles, the combination with upper-fastening means, of a support for a form movable to present the heel-end portions of an insole and an upper on the form to said fastening means, mechanism movable with said support for engaging the upper forwardly of its extreme rear end to control it during the movement of the support, said mechanism comprising members movable laterally of the form to clamp the upper against the sides of the form and movable thereafter heightwise of the form to clamp the margin of the upper on the insole over the bottom of the form.

41. In a machine for fastening uppers to insoles, the combination with upper-fastening means, of a support for a form movable to present the heel-end portions of an insole and an upper on the form to said fastening means, mechanism movable with said support for engaging the upper forwardly of its extreme rear end to control it during the movement of the support, said mechanism comprising arms mounted for swinging movements laterally of the form to clamp the upper against the sides of the form and movable thereafter bodily heightwise of the form to clamp the margin of the upper on the insole over the bottom of the form.

42. In a machine for fastening uppers to insoles, the combination with upper-fastening means, of a support for a form movable to present the heel-end portions of an insole and an upper on the form to said fastening means, mechanism movable with said support for engaging the upper forwardly of its extreme rear end to control it during the movement of the support, said mechanism comprising members movable laterally of the form to clamp the upper against the sides of the form and movable also heightwise of the form to clamp the margin of the upper on the insole over the bottom of the form, a treadle, and means for moving said members first laterally of the form by the treadle and for thereafter moving them heightwise of the form by further movement of the treadle.

43. In a machine for fastening uppers to insoles, the combination with upper-fastening means, of a support for a form movable to present the heel-end portions of an insole and an upper on the form to said fastening means, mechanism movable with said support for engaging the upper forwardly of its extreme rear end to control it during the movement of the support, said mechanism comprising arms mounted for swinging movements laterally of the form to clamp the upper against the sides of the form and movable bodily heightwise of the form to clamp the margin of the upper on the insole over the bottom of the form, a toggle for swinging said arms, means for operating said toggle, and a support for said arms yieldingly movable with them heightwise of the form in response to further movement of said operating means after the clamping of the upper against the sides of the form.

44. In a machine for fastening uppers to insoles, the combination with upper-fastening

means, of a support for a form movable to present the heel-end portions of an insole and an upper on the form to said fastening means, clamping mechanism movable with said support for engaging the upper to control it during the movement of the support, a member movable by the operator for moving said clamping mechanism into clamping position, and means for imparting to said support its work-presenting movement by further movement of said member.

45. In a machine for fastening uppers to insoles, the combination with upper-fastening means, of a support for a form mounted for swinging movement in a direction lengthwise of the form to present the heel-end portions of an insole and an upper on the form to said fastening means, clamping mechanism movable with said support for engaging the upper to control it during the movement of the support, a treadle for swinging the support, and means for operating said clamping mechanism also by said treadle.

46. In a machine for fastening uppers to insoles, the combination with upper-fastening means, of a support for a form movable to present the heel-end portions of an insole and an upper on the form to said fastening means, clamping mechanism movable with said support for engaging the upper to control it during the movement of the support, a treadle movable to operate said clamping mechanism and further movable thereafter to impart the work-presenting movement to said support, and spring means for yieldingly resisting the movement of the support to prevent its movement by the treadle until after the movement of the clamping mechanism into operative position.

47. In a machine for fastening uppers to insoles, the combination with upper-fastening means, of a support for a form movable in a direction lengthwise of the form to present the heel-end portions of an insole and an upper on the form to said fastening means, clamping mechanism movable with said support for engaging the upper to control it during the movement of the support, a member movable by the operator to impart to said support its work-presenting movement, means for moving said clamping mechanism into operative position by said member prior to the work-presenting movement of the support, and mechanism for imparting to said form a heightwise movement also by movement of said member after the work-presenting movement of the support.
48. In a machine for fastening uppers to insoles, the combination with upper-fastening means, of a support for a form movable in a direction lengthwise of the form to present the heel-end portions of an insole and an upper on the form to said fastening means, clamping mechanism movable with said support for engaging the upper to control it during the movement of the support, a treadle movable to operate said clamping mechanism and further movable thereafter to impart the work-presenting movement to said support, and mechanism for imparting to the form a heightwise movement by still further movement of said treadle, said last-named mechanism comprising members relatively movable idly by the treadle to prevent heightwise movement of the form during the operation of said clamping mechanism.

RENÉ E. DUPLESSIS.
